UNITED STATES PATENT OFFICE

98,932

DESIGN FOR A SHOE

Carl Goldberg, Haverhill, Mass., assignor to Goldberg Bros. Inc., Haverhill, Mass., a corporation of Massachusetts

Application January 31, 1936, Serial No. 60,909

Term of patent 3½ years

To all whom it may concern:

Be it known that I, Carl Goldberg, a citizen of the United States, residing at Haverhill, in the county of Essex and State of Massachusetts, have invented a new, original, and ornamental Design for a Shoe, of which the following is a specification, reference being had to the accompanying drawing, forming a part thereof, wherein:—

Figure 1 is a plan view of the shoe.

Figure 2 is a perspective, and

Figure 3 is a fragmentary view on a somewhat enlarged scale for the purpose of showing more clearly the corded edges applied to a part of the shoe.

I claim:—

The ornamental design for a shoe, substantially as shown and described.

CARL GOLDBERG.
